(57) **CLAIM**

The ornamental design for an automobile tire tread, as shown and described.

DESCRIPTION

FIG. 1 is a front view;

FIG. 2 is a rear view;

FIG. 3 is a left-side view;

FIG. 4 is a right-side view;

FIG. 5 is a perspective view; and,

FIG. 6 is an enlargement of a portion of the front view.

The broken line depictions of sidewalls and beads are illustrative of environmental structure and the sidewalls extending radially inward from the solid line borders of a tread area of the tire to the innermost broken line depiction of the beads form no part of the claimed design.
